Primary Examiner — Derrick Holland(74) *Attorney, Agent, or Firm* — Seed IP Law Group PLLC(57) **CLAIM**

The ornamental design for a nacelle for a wind turbine, as shown and described.

DESCRIPTION

FIG. 1 is an isometric view of a nacelle for a wind turbine, showing my new design.

FIG. 2 is a front elevational view thereof.

FIG. 3 is a right side elevational view thereof.

FIG. 4 is a left side elevational view thereof.

FIG. 5 is a rear elevational view thereof.

FIG. 6 is a top plan view thereof; and,

FIG. 7 is a bottom plan view thereof.

The broken lines shown represent unclaimed subject matter and form no part of the claimed design.
